(57) **CLAIM**

The ornamental design for a sock package, as shown and described.

DESCRIPTION

FIG. 1 is a front, right perspective view of a sock package showing our new design;

FIG. 2 is a front elevational view of the sock package;

FIG. 3 is a rear elevational view of the sock package;

FIG. 4 is a left side view of the sock package;

FIG. 5 is a right side view of the sock package;

FIG. 6 is a top plan view of the sock package; and,

FIG. 7 is a bottom plan view of the sock package.

The broken lines illustrate portions of the sock package which form no part of the claimed design.
